UNITED STATES PATENT OFFICE.

MARTA KALINOWSKA, OF NEW YORK, N. Y.

HAIR-PIN.

1,194,844.

Specification of Letters Patent. Patented Aug. 15, 1916.

Application filed November 23, 1915. Serial No. 63,122.

To all whom it may concern:

Be it known that I, MARTA KALINOWSKA, a subject of the Czar of Russia, residing at New York, in the county and State of New York, have invented certain new and useful Improvements in Hair-Pins, of which the following is a full, clear, and exact specification.

This invention relates to hair pins, and 10 has for its object to provide an improved hair pin of the type having pivoted prongs adapted to grip part of the hair placed between them for preventing the device from being jarred out, as is so apt to occur in 15 dancing or active exercise.

It is the aim of this invention to produce a hair pin of this type which will effectively hold itself in the hair, but which has the appearance, when in place, of an ordinary 20 hair pin having rigid prongs.

Another object is to so construct the hair pin that the handle or operating end of the movable prong will not be apt to be accidentally displaced and the device thus 25 released from the hair.

Other objects will appear as the description proceeds.

The invention will be first hereinafter described in connection with the accompanying 30 drawings which constitute part of this specification, and then more specifically defined in the claims at the end of the description.

In the accompanying drawings, wherein 35 similar reference characters are used to designate corresponding parts throughout the several views:—Figure 1 is front elevation of a hair pin made substantially in accordance with this invention, a part of the fixed 40 prong being broken away to disclose the rubber strip carried by the movable prong, and the open position of the movable prong being indicated in dotted lines. Fig. 2 is a longitudinal section through the prongs of 45 the hair pin, taken from side to side, the head being broken away, and Fig. 3 is a cross section through the closed prongs of the device.

The hair pin, as illustrated, comprises a 50 fixed prong 1 and a movable prong 2 pivoted together at 3. The fixed prong is so called because it is permanently attached to the ornamental head 6 by the arm 4, whereas the movable prong has a diverging arm 5 which 55 is movable with respect to the head 6, although said arm 5 is purposely made to

closely resemble the arm 4 of the fixed prong and extends into juxtaposition to the head 6, as indicated at 7.

Both prongs are made in channel form, 60 the prong 2 being of less thickness so that it may fold into the channel of the fixed prong 1, as shown best in Fig. 3. The channel in the prong 2 is fitted with a filling strip 8, preferably of rubber, which provides an effective gripping surface within 65 the channel of the fixed prong 1.

The prongs are yieldingly held together in folded or gripping position, as shown in solid lines in Fig. 1, by a spring 9 housed 70 in the channels in the arms 4 and 5. This spring may be positioned by pins 10 and 11 arranged transversely of the channel of the arm 4, while its main portion extends into the channel of the arm 5 and bears upon 75 the base of said channel for holding the prongs closed, as will be readily understood. When it is desired to open or spread the prongs apart, as when the hair pin is to be placed in the hair, it is only necessary to 80 press upon the arm 5 of the movable prong and move it toward the arm 4 of the fixed prong, whereupon the prong 2 will be swung away from the prong 1, as indicated in dotted lines in Figs. 1 and 2. After the 85 prongs have been inserted into the hair in open position, the pressure is removed from the arm 5 and the spring 9 immediately closes the prong 2 upon the prong 1, firmly gripping the hair between them. The channel 90 form of the prongs makes them very strong and rigid, while the rubber strip used in the channel of the movable prong provides a good and tenacious grip on the hair. The arrangement of the end 7 of the 95 arm 5 of the movable prong in juxtaposition to the head, while the latter overhangs and is arranged in the same plane with said arm, makes it almost impossible to accidentally dislodge the movable prong.

Having thus described my invention, what I claim as new and desire to secure by Letters Patent of the United States is:—

1. A hair pin comprising a pair of prongs pivoted together and having 105 oppositely inclined arms at the other side of the pivot, and a head permanently secured to the arm of one prong and overhanging the arm of the other prong for the purpose specified.

2. A hair pin comprising a pair of prongs pivoted together and having 110 di-

verging arms on the other side of the pivot, and a head secured to the arm of one prong and extending across and into juxtaposition to the arm of the other prong and in the 5 plane thereof, for the purpose specified.

3. A hair pin comprising a pair of prongs pivotally connected together, both prongs having channels facing one another, one channel being narrower than the other and 10 adapted to fold into the same and a strip of rubber secured in the narrower channel for the purpose specified.

4. A hair pin comprising a pair of prongs pivotally connected together, one prong hav-

ing a channel into which the inner face of 15 the other prong is adapted to project, and a strip of rubber on the inner face of the other prong for the purpose specified.

5. A hair pin comprising a pair of prongs pivotally connected together and having 20 channeled arms extending at the other side of the pivot, and a spring for yieldingly holding the prongs in closed position, said spring being entirely housed in the channels in said arms.

In testimony whereof I have signed my name to this specification.

MARTA KALINOWSKA.
